UNITED STATES PATENT OFFICE.

LOUIS VERCOUTERE, OF LEBANON, MISSOURI.

SHADE.

No. 905,608.

Specification of Letters Patent.

Patented Dec. 1, 1908.

Application filed October 31, 1907. Serial No. 400,029.

To all whom it may concern:

Be it known that I, LOUIS VERCOUTERE, a citizen of the United States, and a resident of Lebanon, in the county of Laclede and State of Missouri, have invented a new and useful Improvement in Shades, of which the following is a full, clear, and exact description.

The purpose of the invention is to provide a portable shade adapted for use in connection with lamps or lights of all kinds, and to so construct the device that the curtains carried thereby are removable from their supports and can be quickly and conveniently partially or completely folded or partially 15 or entirely spread out upon said supports.

It is a further purpose of the invention to so construct the shade that the curtain supports have independent swinging and vertical adjustment in the frame of the device, 20 and may be reversed when occasion may demand, so as to adapt the curtain as a screen to lights high or low and so as to deflect or interrupt the direct rays of light relatively to any material, object or work to be illuminated, 25 to a greater or lesser extent.

It is another purpose of the invention to provide a construction of frame wherein the curtain supports are not only adjustably held in the frame, but are retained in adjusted position without the aid of set screws or other devices adapted to be manually set.

The invention consists in the novel construction and combination of the several parts, as will be hereinafter fully set forth 35 and pointed out in the claims.

Reference is to be had to the accompanying drawings forming a part of this specification, in which similar characters of reference indicate corresponding parts in all the figures.

Figure 1 is a perspective view of the improved shade showing one curtain stretched out to its full extent and the other curtain folded; Fig. 2 is an enlarged sectional side elevation of the bracket portion of the frame of the device, illustrating the manner in which the curtain supports are held in adjusted position in the frame; Fig. 3 is a detail perspective view drawn upon an enlarged scale, of one of the retaining mediums employed for the curtain supports; Fig. 4 is a front elevation of the shade, the curtain supports being shown in a different position than in Fig. 1; and Fig. 5 is a plan view of the

device drawn upon a smaller scale and illustrating a slight departure in the shape of the curtain supports.

A represents a standard provided with a suitable base 10, and on said standard A a bracket is secured in any suitable or approved manner, and usually this bracket is constructed as is illustrated, comprising an upper plate 11 and a lower parallel plate 12, each of which plates is provided between the standard and its ends with an aperture 13, 55 the corresponding apertures in the two plates being in vertical registry. In addition to the standard A and the bracket above referred to, I employ one or more arms B supported by the standard A, which 60 arms B in their turn are adapted as supports for curtains C that may be made from any 65 desired material.

The arms B are by preference angular in general formation, comprising a horizontal 70 member 14, and a vertical member 15. The vertical members 15 of the arms are passed down through the apertures 13 in the plates 11 and 12 forming the bracket, and where the two members of an arm connect the horizontal member 14 is somewhat 75 arched at 16, so as not to have much bearing upon the outer edge of the upper plate 11, as is shown in Fig. 1, particularly when the members 15 extend downward through the 80 said bracket and the members 14 of the arms out from the upper end portion thereof.

Furthermore the outer ends 17 of the horizontal members 14 of the arms B, are more or less curved so as to offer more resistance 85 to the curtains C when they are folded, preventing their liability at such time to be forced off from their supporting arms; and it may be here remarked that the curtains C may be hinged upon the horizontal members 90 14 of their supporting arms B, in any suitable manner that will permit them to slide on the arms, although the curtains if desired may be secured permanently in an open position on said arms. When the curtains are 95 mounted to slide they are provided at their upper ends with hems 20, rings or the like.

It will be observed that the curtain supporting arms B may be swung forward or rearward and may be adjusted vertically, 100 and one or both of the arms may be inverted, 105 as is shown in Fig. 4. I employ no set screws or manually operated retaining de-

2

vices for the said arms B, or devices that hold the retaining arms in set or adjusted positions, but instead I employ an automatically acting device that consists, when 5 two arms are employed, of oppositely curved and opposing spring plates 18, having recesses 19 at their ends, and these plates have bearing against the opposing faces of the bracket plates 11 and 12, and their recessed end portions engage with the standard A, their outer or convexed portions engaging with the vertical members 15 of the aforesaid arms B, and when the members 15 of the arms B are inserted in the bracket, they 10 place the retaining plates 18 under tension and serve in a most effective manner to automatically hold the said arms B in any position to which they are capable of adjustment.

20 This device is exceedingly simple, and is well adapted for the purpose intended. It is obvious that the curtain supports B, in addition to being raised and lowered and reversed, may be swung forward or rearward 25 at the convenience of the user, as has been stated, to obtain the proper shade relative to the studies or work in connection with which the light may be employed, and by reason of the said adjustment of the device 30 it can be used in connection with lamps placed high or low, or can be used in connection with candles. The device is portable and independent of the lamp or other source of light, and therefore can be conveniently 35 shifted as desired or carried from place to place.

I desire it to be understood that I do not confine myself to any particular formation of the curtain supports B; as for example their 40 upper members 14 may be curved as is

shown in Fig. 5, instead of being substantially straight as is illustrated in Figs. 1 and 4.

Having thus described my invention, I claim as new and desire to secure by Letters Patent, —

45

1. A lamp shade comprising a standard provided near its top with transverse parallel plates, provided in their ends with openings, arms comprising a vertical member slidable through the openings, and a horizontal 50 member for supporting the shade, and tension devices for retaining the arms in adjusted position, said devices comprising oppositely curved spring plates having recesses in their ends for receiving the standard, and 55 engaging the plates, the curved part of the spring engaging the arms.

2. A lamp shade comprising a standard provided near its top with transverse parallel plates provided in their ends with openings, 60 arms comprising a vertical member slidable through the openings, and a horizontal member for supporting the shade, and tension devices for retaining the arms in adjusted position, said devices comprising oppositely 65 curved spring plates having recesses in their ends for receiving the standard, and engaging the plates, the curved part of the spring engaging the arms, said arms having an upwardly curved portion at the junction of the 70 horizontal and vertical portions for the purpose set forth.

In testimony whereof I have signed my name to this specification in the presence of two subscribing witnesses.

LOUIS VERCOUTERE.
